UNITED STATES PATENT OFFICE.

FRANK CARTLIDGE, OF TERRE HAUTE, INDIANA

CUTTER CHAIN AND BARS FOR MINING MACHINES.

Application filed May 13, 1920. Serial No. 380,955.

To all whom it may concern:

Be it known that I, FRANK CARTLIDGE, a citizen of the United States, residing at Terre Haute, in the county of Vigo and State of Indiana, have invented a new and useful Cutter Chain and Bars for Mining Machines, of which the following is a specification.

My invention relates to the construction of cutter chains and cutter bars for mining machines, and in large part particularly to the construction of those links which connect the links carrying the cutter bits.

In the ordinary construction of cutter chains, the links which connect the bit-carrying links are formed of two side members each of which has a pair of integral bosses which mate with similar bosses from the other side member, the bosses from the two side members meeting on a medial line and forming the bearings for the bit-carrying links, and the two side members being fastened together by rivets passing through such bosses. With this construction the wear of the bosses by reason of their bearing action necessitates the replacement of the entire link, and frequently the strain on the links distorts the fastening pins so that it is almost impossible to drive them out.

According to my present invention, I make the links referred to of side pieces without bosses, and form the bearings for the bit-carrying links by separate cross members which are set in sockets on the inner faces of the side members and are continuous between such side members so that there is no medial parting line, and I fasten these cross members in place and prevent them from turning in their sockets by cross pins which pass through such cross members eccentrically thereof. With this construction, the wear on the bearing pieces is localized at the outer surface, and when the wear necessitates new bearing pieces these can be provided without discarding the side pieces, and by reason of the construction stated the fastening pins are easily driven out. With this I also make certain changes in the bit-carrying links and in the cutter bar.

The accompanying drawing illustrates my invention: Fig. 1 is a fragmentary view of one end of a cutter bar with several links of a chain embodying my invention in place therein, one side plate of the cutter bar being removed to show the chain; Fig. 2 is a

section on the line 2-2 of Fig. 1; and Fig. 3 is a medial longitudinal section through a cutter chain embodying my invention.

The cutter bar comprises side pieces 10 spaced apart by a slide member 11 on which the back edge of the cutter chain slides, the slide member 11 being curved at the ends of the cutter bar and being spaced inward from the edges of the side pieces 10 so that the track for the chain is formed on its outer surface between the projecting parts of the side pieces. The side pieces at their edges have inwardly projecting flanges 12 for overlapping the links of the cutter chain as indicated in Fig. 2. These flanges 12 extend closer to the slide member 11 along the straight portions of the chain track than they do at the curved end portions thereof, thus permitting the swinging of the links around the curved ends of the track but guiding them in the straight portions also.

The cutter chain comprises bit-carrying links 15 and intermediate links 16 which connect the bit-carrying links. The bit-carrying links 15 have the usual tenon parts 17 at the ends for projecting between the side plates of the links 16 to provide the pivotal connection between links, and outwardly projecting parts 18 which carry the cutter bits in the usual manner. The central part of each link 15 may project laterally the full width of the chain track, and beneath the flanges 12, in which case it is provided with a shoulder 19 for engaging such flanges 12 on the straight parts of the track.

Each link 16 comprises two side plates 20 each provided on its inner faces with two sockets 21 near the ends, and two cross members 22 which extend between the side plates 20 and are seated in opposite sockets 21 in such side plates, as is clear from Fig. 3. The cross members 22 and the sockets 21 are cylindrical, and the cross members 22 are one-piece members which extend continuously from one side plate to the other. The two side plates of each link are held together by two rivets 23 which pass through the cross members 22 eccentrically thereof and of the sockets 21, so that by reason of such sockets 21 and the eccentric location of the rivets 23 the cross members 22 are effectively prevented from turning in such sockets. The cross members 22 constitute the bearing members, and pass through correspondingly shaped holes in the tenons 17 of the

bit-carrying links 15. All the wear on the cross members 22 occurs on the outer surfaces, because such members are prevented from moving relatively to the rivets 23 and 5 side plates 20.

In order to provide for the sockets 21, the side plates 20 are made of full thickness from the inner edges which bear against the slide frame 11 to a point beyond the rivets, 10 and preferably to the outer side of the sockets as shown, instead of being made of full thickness only at and near such inner edges and thinner throughout the rest of their width to provide a relatively narrow 15 flange at the edges as in the present usual construction. This allows sufficient metal to provide for the sockets 21, and rivets 23.

The outer edges of the side plates 20 co-operate with the inner faces of the flanges 12, as is clear from Fig. 2, to guide the chain. For this purpose, the outer edge of each side plate 20 where it is overlapped by the flanges 12 is flat throughout its middle part, to co-operate with this flange 12 20 through the straight part of the track, where such flange is widest; but at the ends is cut off, obliquely or on a curve 24, to co-operate with the narrow parts of the flanges 12 at the curved ends of the cutter bar, as is clear 25 from Fig. 1. The side plates 20 at least at their ends as shown, project outward between the flanges 12, thus making rabbet 30 grooves of the curved parts 24.

By reason of having the side plates 20 of 35 full thickness to a point beyond the rivets, the flanges on the side pieces 10 are farther out from the slide member 11 than in the usual construction; and for the same reason the shoulders 19 on the bit-carrying links 40 15 are farther from the inner edges of such links than is usual.

In operation, the links articulate on the outer surfaces of the cross members 22 as 45 the cutter chain travels in its tracks. The chain is guided by the action of the guide member 11 and the flanges 12 of the side pieces 10. When the cross members 22 become too greatly worn, the rivets 23 are punched out, and new cross members 22 assembled in

the same side plates 20. This can be done 50 easily and cheaply. The cross members 22 may be made of ordinary round rod, with no machining save the drilling of the holes for the rivets.

I claim as my invention:

1. In a cutter chain for mining machines, a connecting link for connecting the bit-carrying links, said connecting link being formed of two side plates and two circular cross members extending between such side plates and through bearing holes in the bit-carrying links, said cross members being set in sockets in the adjacent faces of the side plates, and rivets passing through said cross members and connecting said side plates, and said side plates being provided at points outwardly beyond said rivets with outwardly facing surfaces for co-operating with guide flanges of a cutter bar, said outwardly facing surfaces being straight through the intermediate part of the length of said side plates and cut off obliquely at the end parts the arc of said oblique cut being greater than the arc of the cross members.

2. In a cutter mechanism for mining machines, the combination of bit-carrying links; connecting links for connecting the bit-carrying links, each of said connecting links being formed of two side plates and two cross members extending between such side plates and through bearing holes in the bit-carrying links, said cross members being set in sockets in the adjacent faces of the side plates, and rivets passing through said cross members and connecting the side plates; and a cutter bar having a chain track for the chain formed by said bit-carrying and connecting links, said chain track having overhanging flanges located outward beyond said rivets and co-operating with outwardly disposed faces on said links, the side plates of said connecting links having portions projecting outwardly between said flanges.

In witness whereof, I have hereunto set my hand at Terre Haute, Indiana, this 8th day of May, A. D. one thousand nine hundred and twenty.

FRANK CARTLIDGE.
